UNITED STATES PATENT OFFICE.

THOMAS E. MURRAY, OF NEW YORK, N. Y.

ELECTRIC SWITCH.

1,091,155.

Specification of Letters Patent. Patented Mar. 24, 1914.

Application filed November 27, 1912. Serial No. 733,781.

To all whom it may concern:

Be it known that I, THOMAS E. MURRAY, a citizen of the United States, residing at New York, in the county of New York and State of New York, have invented a certain new and useful Improvement in Electric Switches, of which the following is a specification.

The invention is an electric switch, constructed to close circuit between terminals through a main fuse, and thereafter to connect a second fuse in parallel with said main fuse.

The invention consists in the construction, hereinafter set forth, whereby said switch may be operated to cut said fuses successively into circuit, and whereby access to the switch is prevented when the circuit is closed.

In the accompanying drawings Figure 1 is a side elevation, showing the movable portion of the switch raised to open circuit, and also the protective casing. Fig. 2 is a transverse section through the fixed and movable portions of the switch. Fig. 3 shows in elevation and partial section the position of the parts of the switch when the circuit is closed through the main fuse only. Fig. 4 shows the position of the parts of the switch when the circuit is closed through both fuses. Fig. 5 is a top view of the device on a reduced scale. In Figs. 2, 3, and 4 the protective casing is omitted.

Similar numbers of reference indicate like parts.

The fixed part of the switch comprises a base block 1, preferably of porcelain or other refractory insulating material, secured in any suitable way to the bottom of the inclosing metal casing 2. In said block is a longitudinal recess, in which are disposed spring clips 3, 4, to which clips the terminals of the line conductor 5 are connected, said conductor entering the casing through openings in its end walls. The spring clips are alike and are constructed in the following manner: The clip 4 comprises a metal plate 6 which is bent back on itself at 7, then upwardly and then downwardly, as shown at 8, to form one arm of the clip. Said plate is secured upon the bottom of the recess in the base block by a screw bolt 9 passing through the bent back portion at 7. Another metal plate 10 is placed upon plate 6 and bent upwardly and then downwardly, as shown at 11, to form the other arm of the

clip. This plate is secured in place by a screw bolt 12 which passes through both plates. The terminals of conductor 5 are provided with metal end pieces 13, having flat projecting plates 14 which are secured by the screws 15 to the upper plates, as 10, of said clips.

The movable part of the switch is constructed as follows: 16 is a carrier of porcelain or other refractory insulating material, suspended on two rods 17, 18, placed as shown in Fig. 3. Said rods pass loosely through openings in the cover 19 of casing 2 and in bosses 20 on the under side thereof, and are connected above said cover by a bar 21. Surrounding said rods and interposed between said bar 21 and the cover are helical springs 22 which normally hold the carrier 16 in raised position. On the under side of carrier 16 are secured by screw bolts 23 two dependent contact plates 24 and 25, which register with and, when the carrier 16 is lowered, enter between the arms of clips 3, 4, as shown in Fig. 3. Each contact plate is bent back on itself to form a loop 26, the said loops receiving metal bars 27. The terminals of a main fuse strip 28 are interposed between the lower members of the loops 26 and plates 29, and are secured by screw bolts 30 passing through said plates 29 and loops 26 and entering bars 27. The body portion of the fuse strip forms a loop with parallel arms which extends upwardly through an opening in the bottom of carrier 16 into a recess 31 in said carrier. At the bend 32 of said loop said strip is carried through an opening in a partition 33, of fiber or other insulating material, which partition extends down between said parallel arms.

On carrier 16 are two contact plates 34, 35, which are bent to lie against the upper surface of said carrier, and against the walls and bottom of the recess in said carrier. Said plates are secured in place by the screw bolts 23. Above the carrier 16 and between the block and the bosses 20 is a second carrier 36, of porcelain or other refractory insulating material, having an opening 38. Extending across said carrier and above the opening 38 is a bar 37, through which passes the threaded end of a rod 39, said end being secured to said bar by a nut. The rod 39 passes loosely through openings in the cover 19 and the bar 21, and on its upper end has a head 40, between which and said bar is a helical spring 41 which nor-

mally keeps the carrier 36 in elevated position and separated from the carrier 16, as shown in Fig. 3. On the under side of carrier 36 are two contact plates 42, 43, which 5 register with the contact plates 34, 35 on carrier 16. Secured to said plates and extending across the opening in carrier 36 is a fuse strip 44.

In order to break circuit between the terminals of line conductor 5, the carriers 16 and 36 are both raised by hand, the contact plates 24, 25 being then withdrawn from the spring clips 3, 4, as shown in Fig. 1, and supported in their raised position by helical springs 22. In order to establish circuit through the main fuse 28, the bar 21 is pushed down to engage the plates 24, 25 into said clips, as shown in Fig. 3. In order to establish circuit also through the second fuse 20 44, the rod 39 is pushed down until the contacts 42, 43 on carrier 36 meet the contacts 34, 35 on carrier 16. The two fuses 28 and 44 are then in parallel.

As an illustration of a use of this device; 25 in starting a motor, circuit may first be closed through both fuses 28 and 44 to take the initial rush of current, and then after the motor has started, the fuse 44 may be raised out of circuit, leaving only the main 30 fuse 28 in action. The cover 19 is downwardly flanged on both sides, and at one end. Its other end, when said cover is placed upon the casing 2, passes under a flange 45, Fig. 1, on the end wall of said casing. In 35 the end flange is an opening to receive a slotted projection 46 on said casing, which projection receives a seal fastening 47. It is to be noted that even after the seal fastening has been removed, the cover cannot be 40 taken from the casing unless the plates 24, 25 are raised out of the spring clips 3, 4. Then said cover can be slid off the casing in the direction from right to left of Fig. 1.

I claim:

45 1. An electric switch, comprising a support, circuit terminals thereon, a hollow movable carrier, a fuse in said carrier hav-

ing terminals on the exterior thereof coöperating with said circuit terminals, a second carrier movable independently of said first 50 carrier, and a fuse on said second carrier having its terminals coöperating with the fuse terminals on said first carrier.

2. An electric switch, comprising a support, circuit terminals thereon, a hollow 55 movable carrier, two pairs of contacts thereon, the members of each pair being connected, a fuse in said carrier connected to said pairs, a second carrier movable independently of said first carrier, and a fuse on said 60 second carrier having its terminals coöperating with a member of each of said pairs of contacts; the remaining members of said pairs coöperating with said circuit terminals.

3. An electric switch, comprising an in- 65 closing casing, fixed circuit terminals therein, a movable carrier, contacts on opposite sides of said carrier, rods extending from said carrier through a wall of said casing, a connecting device for said rods outside of 70 said wall, springs interposed between said device and said wall, a second movable carrier interposed between said first carrier and said wall, contacts on said carrier, a rod extending from said second carrier through 75 said wall and connecting device, a head on said rod, and a spring interposed between said head and said connecting device.

4. An electric switch, comprising a cas- 80 ing, a slidable cover thereon, means for preventing lifting of said cover from said casing, a movable switch member supported on said cover, and a fixed switch member engaging with said movable member and disposed within said casing; whereby upon the 85 engagement of said switch members removal of said cover from said casing by sliding as aforesaid is prevented.

In testimony whereof I have affixed my signature in presence of two witnesses.

THOMAS E. MURRAY.
